UNITED STATES PATENT OFFICE.

BERNARD H. PAYTON, OF PROVIDENCE, RHODE ISLAND.

DESIGN FOR AN AUTOMOBILE ARM REST.

Application filed March 13, 1928. Serial No. 25,827. Term of patent 14 years.

To all whom it may concern:

Be it known that I, BERNARD H. PAYTON, a citizen of the United States residing at Providence, in the county of Providence and State of Rhode Island, have invented a new, original, and ornamental Design for an Automobile Arm Rest, of which the following is a specification.

In the accompanying drawings which form

a part of this specification Figures 1 and 2 are a plan view and a side view respectively of an automobile arm rest showing my new design.

I claim:

The ornamental design for an automobile arm rest, as shown.

BERNARD H. PAYTON.
